UNITED STATES PATENT OFFICE.

ALBERT H. STEBBINS, OF LOS ANGELES, CALIFORNIA.

SCREEN.

Application filed February 10, 1926. Serial No. 87,879.

This invention relates to screens, and more particularly to a novel construction for preventing clogging of the screening apertures.

Much difficulty is experienced in operating apertured screens due to the tendency of the larger particles to lodge in the screen apertures and clog the same; and in an effort to overcome this difficulty various forms of operating means have been proposed for shaking the screening surface with sufficient force to dislodge the clogging particles. This method of preventing clogging is open to the objection that the energetic movement imparted to the screening surface to dislodge the particles from the apertures may seriously disturb the proper sifting or screening operation.

The present invention therefore relates to a screen the screening surface of which is so constructed that the materials being treated are prevented from lodging in the apertures to clog the same.

One important feature of the invention resides in a screen surface having screening apertures in the form of slots that increase in width in the direction in which they extend so that the particles that lodge in the slots may more readily slide therein in the direction in which the width of the slot increases.

Another important feature of the invention resides in the arrangement of deflectors having inclined walls adapted to force the particles out of the slots in which they have become lodged.

Another feature of the invention resides in the construction of the material supporting surface whereby the materials being treated are directed toward the apertures by sloping walls.

Other features of the invention and novel combination of parts in addition to the above will be hereinafter described in connection with the accompanying drawings which illustrate one good, practical form of the invention.

In the drawings:—

Fig. 1 is a top plan view of a screen constructed in accordance with the present invention;

Fig. 2 is a side elevation of the screen of Fig. 1 shown mounted upon a supporting frame and part of the screen casing being broken away to show the material supporting surface;

Fig. 3 is a perspective view looking to-

ward the discharge end of the screen shown in Fig. 1;

Fig. 4 on an enlarged scale is a sectional perspective view of a portion of the screening surface of Fig. 3;

Fig. 5 on an enlarged scale is a top plan view of a portion of the material supporting surface of Fig. 3;

Fig. 6 is a vertical sectional view through Fig. 5; and

Fig. 7 is an end view of a modified screen construction having an upper and a lower screening surface.

The screen casing which supports the screening surface formed in accordance with the present invention may be given any desired construction and various means might be provided for supporting the screen casing and for imparting a vibratory movement to the same.

The screen casing shown in the drawings is provided with the floor 10 upon which the finer materials fall upon passing through the screen surface. At the opposite sides 80 of the floor 10 are provided the side walls 11 and the frame casing is shown as being rectangular in shape and has the feed hopper 12 provided at the left-hand end thereof. The rate at which the materials flow from 85 the feed hopper to the screening surface may be controlled by adjusting the gate 13. The floor 10 of the casing is preferably mounted upon a carriage or supporting frame conveniently formed of the angle 90 irons 14 disposed at each side of the casing and extending lengthwise thereof, and these angle irons may be connected by the transversely extending braces 15, constituting a rigid frame which will support and strengthen 95 the casing.

The screen casing shown in Fig. 1 is preferably mounted for vibratory movement in the direction of its length and it may be supported in a horizontal plane, but in many 100 cases it will be found desirable to incline the screen in the direction of its length to thereby promote travel of the materials lengthwise of the casing toward the right-hand end thereof, viewing Figs. 1 and 2. In 105 some constructions it may even be desirable to incline the screen casing in the opposite direction to impart a slight uphill movement to the materials as they travel lengthwise of the screening surface.

Various constructions might be provided for mounting the screen frame upon a sup-

porting base for back and forth movement and the supporting means shown comprises a frame formed of the longitudinally extending beams 16 fastened to the uprights 17 and it should be noted that the frame slopes in the direction of its length to support the screen casing at an inclination which will advance the materials lengthwise of the screen, as clearly shown in Fig. 2. 10 Various means might be provided for supporting the screen casing for movement back and forth in the direction of its length, and the means shown consists of balls or rollers 18 resting in the bearing blocks 19 mounted 15 upon the supporting base, and the upper portion of these balls or rollers are received in bearing blocks 20 secured to the side rails 14 of the casing.

It is desirable to impart a vibratory movement to the casing to promote travel of the materials lengthwise of the same and also to promote sifting of the finer materials through the apertures of the screening surface. To this end either a simple, vibratory 25 movement, or a progressive, vibratory movement may be employed, and the operating means shown consists of a cable 21 having an intermediate portion rigidly secured to the casing by any suitable construction, such as the clamping block 22. One portion of the cable extends from the clamping block 22 in a right-hand direction and is bent around the grooved sheave 23 rotatably supported by the transversely extending shaft 24 supported by the base of the machine and this cable extends downwardly from the sheave 23 to a yielding anchor which may consist of a coiled spring 25 which is confined between a transversely extending beam 26 of the supporting casing and an enlarged head or nut 27 secured to the end of this cable. The portion of the cable 21 extending in a left-hand direction from the clamping means 22 passes around a grooved sheave 28 mounted upon an eccentric 29 which eccentric is secured to or is formed integral with the operating shaft 30 which shaft may be driven by a pulley (not shown), and this shaft is rotatably supported by bearing brackets 31 secured to the supporting frame. This cable extends from the lower side of the sheave 28 to anchoring means such as a bolt 32 fastened to a transversely extending beam by the nuts 33, and the length of the cable 21 may be varied as desired by adjusting the nuts 33.

The operation of the construction just described is such that the spring 25 will continuously urge the material supporting casing in a right-hand direction, and the portion of the cable 21 extending around the sheave 28 will be alternately tensioned and slackened off by the eccentric 29 rotating within this sheave. This will serve to tension the cable to pull the screen casing in

a left-hand direction and then slack off the cable to permit the casing to move in the right-hand direction under the action of the spring 25. Should it be desired to increase the progressive nature of the movement imparted to the casing by the means just described, this may be easily done by bump means consisting of a stop 34 rigidly secured to the supporting base, and of an adjustable bolt 35 carried by the vibratory casing, and which may be adjusted to strike against the stop 34 as the casing approaches the end of its stroke in the right-hand direction. 70

The construction so far described forms no essential part of the present invention, 80 but is illustrated to make clear the operation of the screening surface which will now be described. The screening surface 36 may be formed of sheet metal or other suitable material, and extends across the casing between the opposite sides 11 thereof, as will be apparent from Fig. 3. The surface 36 is so constructed that it forms a series of hills and valleys extending lengthwise of the casing and having the inclined walls 37 85 which meet at their upper edge to form the ridge 38, and slope downwardly toward each other to produce the valley provided with the aperture or opening 39 through which the finer materials may pass to fall upon the 90 floor 10 of the casing.

Within each valley formed by the sloping walls 37 is mounted a roof 40 having the downwardly sloping side walls 41, and each roof is supported over and in spaced relation to an opening 39. These roofs, as shown, are formed of thin material such as sheet metal, and are held in spaced relation to the lower portion of the valleys by posts 42. The parts are conveniently secured in place by the bolts 43 which may extend through drill holes formed in the roofs and posts, and may be clamped in place by tightening the nut 44 at the lower end of each bolt, and which rests against 105 a V-shaped block 45 that engages the lower face of the supporting surface 36.

The posts 42 serve to support the roofs so that the lower edges of these roofs lie in spaced relation to the side walls 37 to form 115 the material receiving slots 46 between the lower edge of these roofs and the side walls 37. It is apparent that the inclined walls 37 and 41 will direct the materials downwardly toward the slots 46 to promote the 120 passage of the finer materials through these slots, and the sifting or screening operation of these materials will be assisted by the vibratory movement imparted to the screen casing.

The larger particles which enter the slots 46, and which are too large to pass therethrough, may tend to become stuck in these slots, and in order to prevent this, in accordance with the present invention, the 125

construction of the slots 46 is preferably such that they increase in width in the direction in which the materials travel lengthwise of the casing. This increase in the width of the slots 46 may be readily produced by arranging the roofs 40 in the overlapping relation best shown in Fig. 6, wherein it will be seen that the left-hand end of one roof rests upon the upper end of a post 42, while the right-hand end of this roof overlaps the left-hand end of the next roof, so that the right-hand end of each roof is spaced from its post a slight distance, thus increasing the width of the slots 46 in the direction of their length. This tapered construction of the slots 46 prevents in a very satisfactory manner the lodging of the larger particles in the slots so that they become wedged therein.

If the screening surface is made relatively long as shown, it will be desirable to form the material receiving slots 46 of a number of successively tapered portions so that when the width of the slot at the end of one section thereof has reached the maximum size desired, the slot may be terminated and the materials may pass on to the next tapered slot of similar construction, and in alignment with the first slot.

It is important to provide means for forcing the larger particles within a slot out of the same as these particles approach the end of one of the tapered sections; this is readily accomplished in accordance with the present invention by constructing the posts 42 to form deflectors having the inclined walls 47; that is, these posts, as will be apparent from Fig. 5, are given a wedge-shaped construction with the narrow portion of the wedge extending toward the material receiving end of the screen casing. As a result of this construction, the larger particles designated by α as lying within a slot 46 and traveling lengthwise thereof under the influence of the movement imparted to the supporting casing, will engage a sloping side wall 47 of a post and will be forced out of the slot, as will be apparent from Fig. 5. In this manner all danger of the slots 46 becoming clogged is avoided.

The fine materials which sift through the slots 46 and fall upon the bottom 10 of the casing will travel lengthwise of this floor to the tapered discharge hopper 48 having a downwardly extending pipe 49 which may be connected with a material receiving receptacle by the flexible tube 50. The larger particles which fail to pass through the slots 46 will travel lengthwise of the apertured surface to be discharged from the right-hand end of the casing, viewing Fig. 2, and slide down the discharge board 51.

A screening casing constructed in accordance with the present invention may be provided with a single screening surface such

as 36, as shown in Figs. 2 and 3, or may have two screening surfaces 36 positioned one above the other, as shown in the modified construction of Fig. 7.

From the foregoing description, when read in connection with the drawings it will be seen that the sloping side walls 37 and the sloping roofs 40 serve to direct the materials toward the slots 46, and that the tapered construction of these slots promotes travel lengthwise of the slots of the larger particles which tend to become wedged therein. It will also be seen that these larger particles which tend to lodge in a slot will travel lengthwise therein until they engage the sloping side walls 47 of a post, whereupon they will be forced out of the slot by the tapered construction of the post, thus preventing the slots of the screening surface from becoming clogged.

What is claimed is:

1. A screen, comprising in combination, a casing provided with a material supporting surface constructed to form a series of hills and valleys extending lengthwise of the casing and having sloping side walls and material discharge openings formed in the valleys between the side walls, roofs mounted in the valleys over said openings and having edges that lie in spaced relation to said sloping walls, each roof being formed of aligned sections having their ends overlapped to provide tapered material receiving spaces between the sections and side walls which increase in width throughout the length of each section, but do not increase in width continuously throughout the length of the valleys, and means for imparting movement to the materials being treated to sift the finer materials through the slots formed between said edges and the sloping side walls.

2. A screen, comprising in combination, a casing, a material supporting surface supported by the casing and constructed to form a series of sloping side walls having material discharge openings in the valleys between the side walls, roofs mounted in said valleys above the openings and having side edges that lie in spaced relation to the sloping side walls, wedge-shaped blocks mounted in the valleys at intervals along the same and having tapered sides disposed to force out of the slots the large particles that tend to lodge therein, and means for advancing the materials over said surface to sift the finer materials through the spaces between the edges of the roof and sloping walls.

3. A screen, comprising in combination, a casing provided with a material supporting surface having a series of oppositely sloping side walls, roofs mounted in the valleys and having sloping sides and edges that lie in spaced relation to said side walls

to form material receiving slots toward which the materials are directed by the slope of the roof and the slope of said side walls, each roof being formed of aligned sections having their edges positioned to form successively tapered material receiving spaces between the sections and side walls which increase in width throughout the length of each section but do not increase in width 10 continuously throughout the length of the valleys, and means for imparting movement to the materials being treated to sift the fine materials through said slots.

4. A screen for separating materials comprising in combination, a casing provided with a material supported surface having a series of oppositely sloping side walls constructed to form material discharge openings in the valleys between the side walls, 20 roofs mounted in the valleys so that they lie over said openings and over the lower portions of said sloping side walls and provided with side edges that lie in spaced relation to said side walls to form material receiving slots therebetween, said slots being formed of aligned successively tapered portions that increase in width in the direction in which the materials travel along the slots, deflectors positioned to force out of the 30 slots the large particles that tend to lodge therein, and means for advancing the materials along the supporting surface to sift the finer materials through said slots.

5. A screen, comprising in combination, a casing mounted for vibratory movement and provided with a material supporting surface having a series of sloping side walls and material discharge openings in the valleys between the side walls, roofs mounted in 35 the valleys over said openings and having

side walls to form material receiving slots toward which the materials are directed by the sloping walls, deflectors mounted beneath the roofs and having tapered sides adapted to force out of the slots the large 45 particles that tend to lodge therein, and means for vibrating the casing to advance the materials lengthwise of the same.

6. A screen, comprising in combination, a casing mounted for vibratory movement and 50 provided with a material supporting surface constructed to form hills and valleys extending lengthwise of the casing and having discharge openings formed in the valleys, roofs mounted in the valleys over 55 said openings and having side edges that are spaced from the sloping side walls of the valleys to form discharge slots, posts for supporting the roofs and having inclined side walls adapted to force out of the slots 60 the large particles that tend to lodge therein, and means for vibrating the casing to advance the materials lengthwise of the same.

7. A screen, comprising in combination, a casing mounted for vibratory movement and 65 provided with a material supporting surface constructed to form hills and valleys extending lengthwise of the casing, roofs mounted in the valleys and supported in spaced relation to the sloping side walls of 70 the valley to form material receiving slots through which the fine materials may escape, deflectors mounted adjacent said slots and having tapered walls to force out of the slots the heavier particles that tend to lodge 75 therein, and means for advancing the materials along the supporting surface.

In testimony whereof, I have signed my name to this specification.

ALBERT H. STEBBINS.
